(57) **CLAIM**

The ornamental design for an inflatable seat, as shown and described.

DESCRIPTION

FIG. 1 is a perspective view of the inflatable seat.

FIG. 2 is a front elevation view of the inflatable seat.

FIG. 3 is a rear elevation view of the inflatable seat.

FIG. 4 is a right side of the inflatable seat.

FIG. 5 is a left side view of the inflatable seat.

FIG. 6 is a top plan view of the inflatable seat; and,

FIG. 7 is a bottom plan view of the inflatable seat.

In the drawings, the broken lines depict environmental subject matter only and form no part of the claimed design.
